UNITED STATES PATENT OFFICE.

ROBERT E. L. JANNEY, OF CHICAGO, ILLINOIS, AND MALCOLM T. MACPHERSON, OF ALLIANCE, OHIO, ASSIGNEES TO AMERICAN STEEL FOUNDRIES, OF NEW YORK, N. Y., A CORPORATION OF NEW JERSEY.

CAR-COUPING.

1,202,849.

Specification of Letters Patent.

Patented Oct. 31, 1916.

Application filed September 13, 1915. Serial No. 50,304.

To all whom it may concern:

Be it known that we, ROBERT E. L. JANNEY and MALCOLM T. MACPHERSON, citizens of the United States, and residents of Chicago, county of Cook, and State of Illinois, and Alliance, county of Stark, and State of Ohio, respectively, have invented certain new and useful Improvements in Car-Couplings, of which the following is a specification.

The invention relates to railway cars and has particular reference to novel means for coupling cars, one of which is equipped with a standard coupler and the other with a chain and hook arrangement.

It is common practice in all foreign countries to couple railway cars by means of a chain and hook, a hook being carried by each car and a chain serving to connect the two cars. At each side of the car at the ends are provided buffers or resilient plunger. In some of the foreign countries steps are being taken toward the adoption of a standard coupler such as is in use in the United States, but inasmuch as the transition from one type to another can not be made simultaneously, means must be provided for coupling cars equipped with the old and new apparatus and an object in the present construction is to provide such means as may readily and cheaply be applied to the standard couplers.

The invention will be more readily understood by reference to the accompanying drawings wherein—

Figure 1 is a plan view showing the ends of two cars, one of the foreign type and one of the type as revised. Fig. 2 is a sectional view showing the apparatus used for connecting a standard coupler to a hook. Fig. 3 is a similar view showing the parts in position for coupling; and Fig. 4 is a view showing the emergency coupling means in inactive position.

In the drawings the car 10 is seen to be provided with buffers 11 at the sides of the car, these buffers being resiliently mounted. At the center of the car a hook 12 is provided and a chain 13 is intended as a means for connecting adjacent cars. In the construction shown the car 14 is provided with a coupler 15 having the standard M. C. B. lines. 15' is any ordinary or preferred form of dead block and carrying iron permitting lat.

eral movement of the automatic coupler on the car. At the sides the car is provided with rigid bumpers 16 which engage with the buffers 11 of the adjacent car. Below the coupler and near the center thereof is provided an apertured lug 17 to which is pivoted a lever 18, the upper end of which has a yoke or pair of links 19 connected thereto. To the other end of the yoke is connected a crank 20, the pivot of which occupies a recessed lug 21 on the top of the coupler. A projection or boss 22, preferably hollow to form a socket, on the crank provides for the insertion of any convenient rod or bar to form an operating handle or lever. In the position of Fig. 3 the lever 18 is swung outwardly to the extent permitted by the yoke 19 and crank 20 and the chain 13 which is connected to the lever is thereby lengthened sufficiently to permit it to engage the hook 12 of the adjacent car. This is the position the hook will assume when the cars are in abutting engagement, as shown in Fig. 1, and without compression of the spring buffers 11. After the hook has engaged the chain the lever or handle 23 is grasped and the crank 20 is swung around its pivot into the full-line position of Fig. 2 in which position a horizontal pull on the yoke will be ineffective to disengage the parts due to the fact that the crank has swung past center. It will, of course, be understood that the chain is long enough to permit convenient engagement with the hook, and consequently there is some slack in the chain when engaged with the hook, which slack is very conveniently and effectually taken up by the present device by moving the lever 18 from the position shown in Fig. 3 to the position shown in Fig. 2. This movement is accomplished by means of the part 20 which constitutes a toggle and locks the device when thrown over into its position in Fig. 2, the pivotal connection between the part 20 and the links or yoke 19 being below the fulcrum of the part 20, whereby any pull on the chain tends to hold the part 20 down instead of moving it in an upward direction. In the dotted line position of Fig. 3, which is the normal position of the parts when the cars are locked or coupled, it will be seen that the chain cannot escape from the hook. In the position of Fig. 2 the buffers have been compressed to their full

extent, thus providing some slack in the chain, for inasmuch as this is an abnormal position and one which can not occur in coupling, the provision for lengthening the chain is made.

The apparatus described is useful only when coupling a car having the old and new equipment. When two cars having the modern equipment are to be coupled the lever, yoke and keeper are disengaged and swung downward, as shown in Fig. 4, and may be attached to some convenient portion of the car.

It will be noted that we have used rigid buffers on the car having an automatic coupler, of the usual length of head, which arrangement permits the coupler head to extend beyond the end sill a sufficient distance to permit convenient engagement of the chain with the hook coupler.

We claim:

1. Coupling means for railway cars comprising in combination a Janney type coupler, a coupler chain, and a lever pivoted in the throat of the coupler and associated with the chain for taking up slack therein with the hook of an opposing coupler, substantially as described.

2. Coupling means for railway cars comprising in combination a Janney type coupler, a coupler chain, a lever pivoted to the coupler and adapted to be swung outside of the operative limits thereof into an inoperative position, and means permitting limited swinging movement of said lever and also constituting lever actuating means for taking up slack in the chain, substantially as described.

3. Coupling means for railway cars comprising in combination a Janney type coupler, a lever lying in the throat of the coupler and pivoted at one end to the coupler, a link connecting the other end of the lever to the coupler and adapted to permit a limited swinging movement of the lever, and a chain connected to the lever, substantially as described.

4. A car coupler of the M. C. B. type provided with a coupling chain for connection with the hook of a European type of coupler, and also provided with means other than the chain for taking up the slack in the chain after engagement with the hook.

5. A car coupler of the M. C. B. type provided with a coupling chain for connection with the hook of a European type of coupler, and also provided with means for taking up the slack in the chain after engagement with the hook, said means including a toggle.

6. A car coupler of the M. C. B. type provided with a coupling chain for connection with the hook of a European type of coupler, means for taking up the slack in the chain after engagement with the hook, said

means including a lever fulcrumed on the coupler head and having the chain connected thereto, and a toggle mounted on the head and connected to the lever.

7. A car coupler of the M. C. B. type provided with a coupling chain for connection with the hook of a European type of coupler, means for taking up the slack in the chain after engagement with the hook, a lever fulcrumed upon the coupler head and mounted to swing in a vertical plane within the throat of the coupler, the chain being carried by the lever, and means mounted on the coupler head and associated with the lever for moving the same into an upright position within the throat of the coupler to take up slack in the chain.

8. A car coupler of the M. C. B. type provided with a coupling chain for connection with the hook of a European type of coupler, means for taking up the slack in the chain after engagement with the hook, a lever fulcrumed at the bottom of the coupler head and mounted to swing in a vertical plane into an upright position within the throat of the coupler, the chain being carried by the lever, and detachable means for moving the lever into its upright position, said lever and chain capable of being moved to an inoperative position out of the throat of the coupler when the detachable means is detached.

9. A car coupler of the M. C. B. type provided with a coupling chain for connection with the hook of a European type of coupler, means for taking up the slack in the chain after engagement with the hook, said means including a lever fulcrumed upon the car coupler head and carrying the chain, a keeper on the coupler head and provided with a fulcrum notch, and a toggle pivoted to the lever and having a fulcrum for detachable engagement with the fulcrum notch, whereby the lever may be moved to normal or coupled position to take up slack in the chain, the pivots of the toggle being out of alignment in the coupled position of the lever to lock the same.

10. A car coupler of the M. C. B. type provided with a coupling chain for connection with the hook of a European type of coupler, means for taking up the slack in the chain after engagement with the hook, said means including a lever fulcrumed at the bottom of the coupler head to swing vertically into and out of the throat of the coupler, the chain being carried by the lever, a fixed fulcrum member rising from the top of the coupler head and provided with a fulcrum notch open at the rear end thereof, and a toggle including a yoke pivoted to the lever and adapted to straddle the fulcrum member, and a second yoke pivoted between its ends within the first-mentioned yoke and provided with a cross bar for detachable

gagement with the notch of the fulcrum member.

11. A car coupler of the M. C. B. type provided with means for connection with the hook of a European type of coupler, said means being located in the throat of the coupler between the guard arm and the pivoted knuckle and back of said knuckle and adapted to coöperate with the hook cou-

pler independently of the pivotal knuckle of 10 the M. C. B. coupler.
